UNITED STATES PATENT OFFICE.

GIDEON FRISBEE, OF PHILADELPHIA, PENNSYLVANIA.

PULVERIZING-MACHINE.

SPECIFICATION forming part of Letters Patent No. 627,579, dated June 27, 1899.

Application filed June 1, 1898. Serial No. 682,260. (No model.)

To all whom it may concern:

Be it known that I, GIDEON FRISBEE, a citizen of the United States, residing at Philadelphia, county of Philadelphia, and State of Pennsylvania, have invented a new and useful Improvement in Pulverizing-Machines, of which the following is a full, clear, and exact specification.

My invention relates to an improvement in pulverizing-machines, and more particularly to the discharge apparatus in connection therewith.

The object of my invention is to provide a discharge apparatus for a pulverizing-machine by means of which a uniformity of product is delivered without waste or loss of the material to be pulverized, the pulverized material being automatically fed to the apparatus and discharged therefrom. The discharge apparatus may also be adjusted so as to permit only granules of a desired size to pass therethrough, coarser particles being returned to the pulverizing-chamber to be further acted upon.

My invention is illustrated by the accompanying drawings, in which—

Figure 1 is a side elevation of a pulverizing-machine provided with my improved discharge apparatus. Fig. 2 is an enlarged sectional elevation of the pulverizing-chamber and the discharge apparatus; and Fig. 3 is a cross-section of the discharge apparatus on the plane of the line $x x$, Fig. 2.

Similar letters refer to similar parts.

In describing my invention I have illustrated it as attached to one form of pulverizing-machine, in which A is a casing carrying movable pulverizing-rolls B B, carried by a shaft D, the said rolls being revolved rapidly within the casing A, so that by centrifugal action they press outwardly against the ring-die E, crushing or breaking such substances as may be between the said die and the adjacent surfaces of the rolls. In this form of machine a circulation of air is produced tending to throw any substance contained within said casing away from the center and toward the surface of the die. The shaft D is driven by any suitable means.

F is a casing located adjacent to the end of the pulverizing-chamber, said end of the pul-

verizing-chamber opening into the interior of the casing F.

G is a screen carried within said casing F and mounted upon a frame H, which is in turn mounted upon a revoluble shaft I.

J is a rim supported by arms K K, carried by and forming, by preference, part of the frame H.

The screen G is cup-shaped, the side walls 60 diverging. The wider end of the cup-shaped screen faces the opening in the pulverizing-chamber, the lower edge of the said screen being located above the lowest point in the inner periphery of the ring-die E, for the purpose hereinafter described. If desirable, a supplemental screen L may be provided, as shown, the mesh of the inside screen being, by preference, slightly greater than the outside screen G.

M is a gear-wheel carried by the shaft I, which gear is driven by the pinion N through the idler O. The pinion N is mounted upon the shaft P, which may be driven by supplemental means or by a belt connection with the shaft D, as shown in said dotted outline.

Q is a hopper for regulating the feed-supply, the said hopper carrying a distributing-roll of any ordinary construction, driven by means of a gear R, which is by preference actuated in turn by a worm-screw S on shaft P.

In operation the feed-supply is passed through the hopper Q and is directed to the interior of the pulverizing-chamber A, where by means of the rolls B B the same is crushed 85 into a finely-divided state. When the same has been rendered sufficiently fine, it is driven off by the air-currents tending away from the center of the pulverizing-chamber, and the fine particles enter the screen L, which is revolved, preferably, at slower speed. If the material thus driven into the screen is sufficiently fine, it passes through the mesh of the screen or screens and is delivered through the spout T to a suitable receptacle. Coarse particles, which cannot pass through said screen, 90 gravitate back into the pulverizing-chamber by being rolled over and over in the lower part of the screen, which inclines downwardly, so that the tendency of the rotary movement 95 of the said screen is to work the coarser particles in the direction of the pulverizing-chamber.

ber, in which said coarser particles are acted upon until reduced to a sufficiently finely divided state. As above stated, if desirable two or more screens may be used, so as to add 5 to the capacity of the discharge apparatus in handling the produce in process of pulverizing.

The size of the granules delivered from the machine may be varied by substituting 10 screens having meshes of the desired size. In the preferable form the rear ends of the screens are closed by the frame H, which is in substantially the form of the disk.

15 U U are wearing-rings arranged back of the rim J and between said rim and the flanges V. These wearing-rings are provided for the purpose of affording a bearing-surface to the rear of the rim J instead of to the front of said rim. The position of the rim J with respect to the open end of the pulverizer-casing 20 may be adjusted by introducing wearing-rings U of the desired thickness. The disk H may be shifted upon the shaft I, so as to effect the further adjustment of said wearing-rings.

25 It is obvious that in carrying out my invention some changes in the particular construction shown and described may be made, and I would therefore have it understood that I do not limit myself to the specific form shown, but 30 hold myself at liberty to make such changes as are fairly within the spirit and scope of my invention.

Having thus described my invention, what I claim, and desire to secure by Letters Patent, is—

35 1. In a pulverizing-machine, in combination, a pulverizing-chamber, a stationary ring-die and revoluble rolls therein, and a discharge

apparatus comprising one or more cup-shaped screens located adjacent to one end of the pulverizing-chamber and mounted upon an independently-revoluble frame, the lower edge of said screen or screens being substantially above the lower inner edge of the said ring-die. 40

45 2. In a pulverizing-machine, in combination, a pulverizing-chamber, a stationary die, and revoluble rolls therein, a discharge apparatus comprising one or more cup-shaped screens located outside of and adjacent to one end of the pulverizing-chamber and mounted upon an independently-revoluble frame or holder, the lower edge of said screen or screens being above the plane of the lower edge of the ring-die, a separate casing having a discharge-spout surrounding said screening apparatus, and means for revolving said screens. 50

55 3. In a pulverizing-machine, in combination, a stationary pulverizing-chamber, a stationary ring-die therein, revoluble rolls within 60 said die, a discharge apparatus comprising one or more cup-shaped screens located adjacent to one end of said pulverizing-chamber and mounted upon an independently-revoluble frame, wearing-rings and means for adjusting the position of said revoluble frame, the lower edge of said screen or screens being located substantially above the plane of the lower inner edge of the die, a casing surrounding said screening apparatus, a discharge-spout for pulverized material, and return-passages for unpulverized material. 70
